GARLAND FOR A CHRISTMAS TREE

Jack Burnbaum, Newton, Mass.
(451 D St., Boston, Mass. 02127)

Filed June 13, 1966, Ser. No. 2,658

Term of patent 14 years

(Cl. D29—1)

Fig. 1.

Fig. 2.

Fig. 3.

FIG. 1 is a front elevational view of a Christmas tree, showing my new design, the back thereof being substantially similar in appearance,

FIG. 2 is a top plan view, and

FIG. 3 is a side elevational view thereof.

The characteristic feature of my design resides in the combination of the integral stringing of the upper part of the specific partially spiraled icicles with the faceted flat beads, the icicles being spaced apart throughout by a uniform number of beads that are permanently connected thereto in the relationship shown.

I claim:

The ornamental design for a garland for a Christmas tree, substantially as shown and described.
